United States Patent Office

Des. 182,686
Patented Apr. 29, 1958

182,686

SUNGLASS CASE

Lionel Rabb, Pawtucket, R. I.

Application July 25, 1957, Serial No. 47,084

Term of patent 7 years

(Cl. D57—1)

FIG. 1

FIG. 2

FIG. 3

Fig. 1 is a front view of a sunglasses case showing my new design;

Fig. 2 is an end elevational view thereof; and

Fig. 3 is a top plan view thereof in open position.

The dominant features of my design reside in the portions shown in full lines.

I claim:

The ornamental design for a sunglasses case, as shown and described.
